MARKS, OF SEWICKLEY, PENNSYLVANIA

PAPER LATH

Application filed February 13, 1931. Serial No. 515,479.

My invention pertains to paper lath and relates especially to paper lath of the character in which a backing of corrugated paper, or paper-like material, having metallic stiffening devices secured thereto is employed.

In building construction, it has become common to employ what is known as paper lath, that is to say lath constituted by a backing of paper, or paper-like material, to which is applied plaster, concrete or kindred cementitious substances such as are used in building construction, which substances are intended to be included when the term "plaster" is used herein. Paper formed with corrugations has been found to be desirable for the backing, since the plaster, filling the corrugations, is keyed to the backing, and also the corrugations produce projections, at the rear of the backing, which space the lath in a desirable manner from the studding or other support which is to carry the plaster. It is found in practice, however, that such corrugated paper backings tend to sag, and the corrugations thereof to straighten out, when the wet plaster is applied thereto. Various undesirable conditions result from this. For instance, when the lath is employed horizontally, the backing, and the whole body of plaster, is liable to sag downwardly. On the other hand, when the lath is employed vertically, the backing is liable to sag inwardly under the pressure of the trowel or other implement by means of which the plaster is applied, and subsequently, after the plaster has been applied, to spring outwardly, the result being that the surface of the plaster is waved instead of flat. Various means have been proposed from time to time to prevent collapse of the corrugations in such paper backings, and to stiffen the whole backing against sagging. However, such constructions have been expensive and not entirely satisfactory in the results obtained.

Furthermore in the use of paper lath, in unit form, for the support of plaster or the like, it has been found that under certain circumstances cracks appear along the lines where adjoining sections abut or overlap,

owing probably, to the lessened rigidity of the backing, especially when moist, at these locations.

It is the principal object of my invention to provide paper lath including a corrugated paper backing which will be proof against collapse of the corrugations and sagging of the backing, and which will be of an exceptionally economical construction.

It is a further object of my invention to provide paper lath of such character that when adjoining sections thereof are employed a ridge of plaster of increased thickness will be created along the lines of abutment or overlap the adjoining units, thereby preventing the formations of cracks in the finished wall, ceiling or the like.

One form of paper lath embodying my invention is described in the following specification and shown in the accompanying drawing, in which:

Fig. 1 is a front view showing sections of paper lath embodying my invention as applied preparatory to the construction of a wall;

Fig. 2 is an enlarged front view of a corner of a lath unit; and

Fig. 3 is a cross section, taken as on the line III—III of Fig. 2, but showing two adjoining lath sections with the plaster or like applied thereto.

Referring now to the drawing, the section of paper lath shown therein comprises a backing sheet of paper 1 (which term is intended herein to include paper-like materials in general) in which are formed a series of spaced V-shaped corrugations 2. These corrugations run lengthwise of the backing sheet, which is of an elongate rectangular form suitable to span a plurality of the studs 3 or other supports to which the plaster is to be applied, the V-shaped corrugations then running transversely of such studs. In certain of the corrugations 2 (in the instance shown in the top, bottom and middle corrugations) are disposed V-shaped metallic stiffening strips 4 which, in the particular embodiment shown, are of a shape corresponding with that of the corrugations 2 and arranged so that their edges are flush with the surface of

the backing sheet 1, though such shape and arrangement may be varied. Spaced along the length of the backing sheet, at right angles to the corrugations 2, are sheet metal bridge members 5, of U shape in cross section. These members lie flat upon the backing sheet 1 and are secured to such backing sheet by means of staples 6 which are applied in the spaces between the corrugations 2. The staples 10 overlie the bridge members and the operation of applying them causes indentations 5^a (Fig. 3) to be formed in the bridge members at the points where the staples cross the latter. Such indentations prevent any transverse movement of the backing with respect to the bridge members.

When plaster is applied to the backing sheet, the latter becomes moistened, and, in the absence of means for preventing it, the 20 backing sheet would be pushed back under the pressure of applying the plaster, thereby opening out the corrugations. However, by providing the bridge members and securing the latter to the backing sheet by staples disposed in the spaces between the corrugations, as described above, the backing sheet is securely maintained against any material rearward movement under the pressure employed when applying the plaster. Any appreciable flattening out of the corrugations, therefore, is effectively prevented. In this connection, it will be noted that the backing sheet, under the tendency to be pushed rearward, cannot slip transversely with respect to the 30 bridge members, because of the fact that the staples are locked in the indentations of the bridge members. The corrugations, therefore, are maintained in shape by obviating the cause which would tend to distort them.

40 The longitudinal edges of the backing sections are bent downward, as indicated at 1^a, preferably to such an extent that their margins are substantially level with the bottoms of the corrugations. The bridge members 45 are preferably likewise bent downward, as indicated at 5^a. The lath sections are applied to the studs 3, usually by nails 7 driven through the longitudinal stiffening members 4 and into the studs. When a second lath 50 section is secured in place to the studs with its edge abutting, or slightly overlapping, the edge of another lath section, a channel-shaped depression, is formed, which, when the plaster 8 is applied, provides a ridge 8^a of 55 plaster along the line of juncture of the lath sections. Such ridge strengthens the plaster along the line where the sections join and effectively prevents the appearance of cracks along that line, the formation of which cracks 60 has heretofore been a trouble frequently experienced in the use of paper lath sections of the general character herein referred to.

I claim:

65 1. Paper lath comprising a paper backing sheet formed with longitudinal corrugations,

individual bridge members extending transversely of said corrugations and formed with indentations at points disposed in the spaces between said corrugations, and staples resting in said indentations and entering said backing sheet to secure said bridge members thereto, whereby relative transverse movement between said backing sheet and said bridge members is prevented and said sheet is supported against such movement with respect to the bridge members as would tend to distort said corrugations.

70 2. A paper lath section comprising a paper backing sheet formed with longitudinal corrugations, stiffening members in said corrugations, individual bridge members extending transversely of said corrugations and stiffening members, and means for securing said bridge members to said backing sheet, the longitudinal edges of said backing sheet 80 being bent rearwardly, whereby a channel is created at the line of juncture of two adjoining sections to provide a strengthening ridge 85 of plaster at such line.

90 In testimony whereof, I sign my name. HERBERT E. MARKS.
